UNITED STATES PATENT OFFICE.

JOHN W. RICHARDS, OF MUSCATINE, IOWA.

AWNNG-FRAME.

No. 909,119.

Specification of Letters Patent.

Patented Jan. 5, 1909.

Application filed July 22, 1908. Serial No. 444,734.

To all whom it may concern:

Be it known that I, JOHN W. RICHARDS, of Muscatine, in the county of Muscatine and State of Iowa, have invented certain new and useful Improvements in Awning-Frames; and I hereby declare that the following is a full, clear, and exact description thereof, reference being had to the accompanying drawings, which form part of this specification.

10 This invention is an improvement in awning frames and its object is to provide means for suspending an awning from a wall, and it consists in novel foldable awning supporting frames which can be arranged above the awning roll and will automatically distend the awning sheet as it is unwound from the roll and will hold it in extended position; and which can be closed by the pull of the awning sheet as it is rewound on the roll.

20 A further object of the invention is to so construct the frames that they can be located above the awning roll and above the cornices of the windows of stores or buildings to which the awning is connected, the awning being practically suspended by the frames instead of upheld thereby, and the awning frames can be above the awning and out of the way at all times and are especially adapted for use over display windows of 30 stores, as the frames will not obstruct the view of the windows nor be in the way of persons passing along the sidewalk.

The invention is particularly applicable to stores which have all glass fronts and where 35 there is no place below the cornices or tops of the window frames for attachment of the ordinary awning supports.

The invention will be clearly understood from the following description in connection 40 with the accompanying drawings, in which—

Figure 1 is a perspective view of one of the awning frames shown supporting the awning extended. Fig. 2 is an enlarged side elevation of the frame partly distended, in full lines, and folded, in dotted lines; and Fig. 3 is a detail-sectional view on line 3—3, of Fig. 2.

The awning support comprises two similar extensible and foldable frames one at each end of the awning and constructed alike so 50 that the description of one will describe and explain both. Each frame comprises a main member or lever 1 which is hinged at 1^a to a wall bracket 8 secured to the wall of the building to which the awning is to be attached, and above the awning roll R.

To the lever 1, near the outer end thereof,

is pivoted, at 6^a, one end of a hanger bar 6, to the lower end of which is fastened one end of the awning pole P, to which the outer side of the awning sheet S is attached. The pole 60 P is attached to and between the lower or free ends of the bars 6, of the two frames, and is supported thereby. To lever 1, at a point intermediate the pivots 1^a and 6^a is pivoted, at 2^a, a brace lever 2. And to the outer end 65 of lever 2 is pivoted, at 2^c, a slide 2^b, which slidably engages the bar 6, which can freely move through said slide. To the main lever 1, adjacent bracket 8, is pivoted, at 4^a, a link 4, the lower end of which is connected by a 70 pivot 4^b to one end of a link 3 the other end of which is pivoted, at 3^a, to lever 2, intermediate the slide 2^b and pivot 2^a. To pivot 4^b is also connected the lower end of a suspending rod 5, the upper end of which is pivoted, at 5^a, to a bracket 8^a attached to the wall above the bracket 8. The links 3 and 4 form a 75 toggle-lever which will be distended by the lowering of lever 1, and will force brace lever 2 to swing outward and upward toward lever 1; and brace 2 will in turn cause hanger bar 6 to swing outward and upward.

The frame operates much after the manner of a lazy tongs, being distended by the action of the toggle-lever 3—4—when main lever 1 80 is lowered, and folding when main lever 1 is drawn upward. A weight 7 is placed upon the outer end of lever 1, beyond the pivot 6^a, and this weight is sufficient to cause the distension of the frame, as the awning is unwound from the roll R. The weight 7 is 85 preferably slotted for the passage of lever 1 and is secured thereon in any desired position by means of set-screw 7^a. A guard plate 9 is attached to lever 1 as shown, and 90 extends from a point adjacent pivot 4^a to a point adjacent pivot 2^a. This guard helps to keep levers 1 and rod 5 in contact and also limits the swing of rod 5 and prevents it passing beyond the pivots 4^a or 2^a as the awning 100 is lowered or raised and thus locking the frame. The roll R, to which the inner end of the awning sheet is attached as usual, is preferably operated as described in my Patent #602,772, but any suitable means may be 105 used for rolling and unrolling the awning. When the awning is unrolled the weights 7 cause levers 1 to swing downward and, through the action of the toggle levers, the lower ends of bars 6 are caused to swing outward and thus spread the awning as fast as it 110 is unrolled.

Fig. 2 shows in full lines, the position of the parts when the awning is partly opened, and in dotted lines, the position of the parts when the awning is rolled up. As the awning is rolled up it draws pole P toward roll R and thus closes the frames. It will be observed that in the present instance the frames are or may be arranged entirely above the awning roll; and they can be arranged, if desired, above the cornices of the windows or doors of the building to which the awning is attached, and thus the frames are entirely out of the way and do not obstruct the view beneath the awnings, nor the passageway thereunder. The parts are so arranged that as the awning is closed the pole P rises as it recedes, so that the passageway is not obstructed either during the raising or lowering of the awning. If desired, the members of the frames may be of iron, but the particular cross-section of the iron used is not material, provided it does not interfere with the relative swinging movements of the members.

I have not attempted in the drawings to show the exact relative proportions of the parts as these will be varied according to the weight and spread of the awning. The same frames can be used for different spreads of awnings up to the maximum spread, and the weights 7 can be adjusted so as to cause the awning frames to open automatically according to the spread of the awning. If a 7 ft. spread is desired the weights can be moved back toward the pivots 6^a, and that will reduce the force or pressure on the main lever; and by shifting the weights out toward the ends of levers 1, they will spread the frames sufficiently to stretch the sheet for a 10 ft. spread. The frames are substantially automatic in action and will open of their own accord as fast as the awning sheet is unrolled, and will hold the awning in spread position.

The frames are under perfect control at all times by means of the roll R, and will close up against the building when the awning is rolled up, as indicated in dotted lines Fig. 2.

Having described my invention what I claim as new and desire to secure by Letters Patent is:

50 1. A foldable awning frame comprising a main lever pivotally connected to the wall at one end, a hanger bar pivoted to said lever, a toggle comprising two links one of which is pivotally connected to the main lever adjacent the wall pivot, a connection between the other toggle-link and the hanger bar, and a suspending rod pivotally connected to the wall and to the joint of the toggle, substantially as described.

60 2. An awning frame comprising a main lever pivotally connected to the wall at one end, a hanger bar pivoted to said lever, a toggle comprising two links one of which is pivotally connected to the main lever adjacent the wall pivot, a connection between the

other toggle-link and the hanger bar, and a supporting rod pivotally connected to the wall and to the joint of the toggle; in combination with an awning roll, an awning sheet, and an awning pole connected to said sheet and to the free end of the hanger bar. 70

3. An awning frame comprising a main lever pivoted at one end, a hanger bar pivotally suspended from the main lever, a brace pivoted to said main lever, a slidable connection between the free end of said brace and said hanger bar, a toggle connection between the main lever and said brace, and a swinging support connected with the pivot of said toggle. 75

4. An awning support comprising a main lever pivoted to the wall at one end, a hanger bar pivotally suspended from the main lever near its outer end, a weight on the outer end of the main lever, a brace pivoted to said main lever, a slidable connection between the free end of said brace and said hanger bar, a toggle connection between the main lever and said brace, and a swinging support connected with the wall and the pivot of said toggle. 80

5. An awning supporting frame comprising a main lever pivoted at one end, a hanger bar pivotally suspended from the main lever near its outer end, a brace pivoted to said main lever, a slidable connection between the free end of said brace and said hanger bar, a toggle connection between the main lever and said brace, and a suspending rod pivotally connected to the wall above the main lever pivot, and pivotally connected with the knuckle of the toggle. 95

6. An awning supporting frame comprising a main lever pivoted to the wall at one end, a hanger bar pivotally suspended from the main lever near its outer end, a brace pivoted to said main lever, a slidable connection between the free end of said brace and said hanger bar, a toggle connection between the main lever and said brace, a weight connected with the outer end of said main lever, a suspending rod pivotally connected to the wall above the main lever pivot and pivotally connected with the knuckle of the toggle, and a guard connected with the main lever for limiting the swinging movement of the suspending rod. 105

7. In combination, a pair of frames each comprising a main lever pivoted to the wall at one end, a hanger bar pivotally suspended from the main lever near its outer end, a brace pivoted to said main lever, a slidable connection between the free end of said brace and said hanger bar, a toggle connection between the main lever and said brace and a swinging support connected with the wall and the pivot of said toggle; with a pole connected to the free ends of the hanger bar. 120

8. In combination, a pair of frames, each comprising a main lever pivoted to the wall at one end, a hanger bar pivotally suspended

from the main lever near its outer end, a brace pivoted to said main lever, a slideable connection between the free end of said brace and said hanger bar, a toggle connection between 5 the main lever and said brace, a weight adjustably connected with the outer end of said main lever, and a suspending rod pivotally connected to the wall above the main lever pivot and pivotally connected with the 10 knuckle of the toggle; with a pole connected to the said hanger bars, an awning sheet con-

nected with said pole, and an awning take-up roll connected with said sheet, said awning take-up roll being arranged below the said frames.

15

In testimony that I claim the foregoing as my own, I affix my signature in presence of two witnesses.
